US00D794593S

(12) **United States Design Patent** (10) **Patent No.:** **US D794,593 S**
Lee et al. (45) **Date of Patent:** **** Aug. 15, 2017**

(54) **MOBILE PHONE**

(71) Applicant: **LG ELECTRONICS INC.**, Seoul (KR)

(72) Inventors: **Hophil Lee**, Seoul (KR); **Jihoon Shin**, Seoul (KR); **Hyoni Kim**, Seoul (KR)

(73) Assignee: **LG ELECTRONICS INC.**, Seoul (KR)

(**) Term: **15 Years**

(21) Appl. No.: **29/535,314**

(22) Filed: **Aug. 5, 2015**

(30) **Foreign Application Priority Data**

Feb. 6, 2015 (KR) 30-2015-0006650

(57) **CLAIM**

The ornamental design for a mobile phone, as shown and described.

DESCRIPTION

FIG. 1 is a front perspective view of a mobile phone showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof; and,

FIG. 8 is a rear perspective view thereof.

The broken lines depict portions of the mobile phone that form no part of the claimed design.

1 Claim, 7 Drawing Sheets
